**METHOD AND APPARATUS FOR PROPEL-
LING PROJECTILES FOR SPACE AND
OTHER APPLICATIONS**Gus Francis, 1480 S. Josephine,
Denver, Colo. 80210Continuation of application Ser. No. 439,866, Mar. 15,
1965. This application Jan. 4, 1967, Ser. No. 609,267
16 Claims. (Cl. 102—23)**ABSTRACT OF THE DISCLOSURE**

The invention is a weapon device for hurling without a projectile chamber, flat plate projectiles against a target, and comprises an explosive charge having at least one flat face with a buffer plate having opposed flat faces mounted contiguous to the explosive charge and a flat metal projectile plate mounted contiguous to the buffer plate, the specific improvement being the use of the buffer plate to prevent premature shattering of the metal projectile plate. A modification is the incorporation of the weapon device using opposed metal plates on space vehicles as it is peculiarly adaptable to use in space where a recoilless weapon is required.

Cross reference to related applications

This application is a continuation application of my application Ser. No. 439,866 filed in the U.S. Patent Office on Mar. 15, 1965, and now abandoned.

This invention relates to a method and apparatus for directionally propelling projectiles by means of explosives without the aid of a projection chamber, and to an anti-satellite satellite weapon utilizing the method and apparatus.

This application is related to the co-pending application of James A. Dunn and Gus Francis, Ser. No. 200,-379, filed in the U.S. Patent Office on June 6, 1962, now Patent No. 3,196,791, and entitled, "Method and Apparatus for Propelling Projectiles."

The principal use for the present invention is in anti-satellite satellite applications, that is, the use of explosively propelled projectiles launched from a satellite for the destruction of enemy satellites, or other objects in space. It is peculiarly adapted to space application wherein the absence of air, the medium for forming shock waves by explosives, requires the use of other means than shock waves formed by explosives for the destruction of enemy satellites.

The invention is also adapted for the use of explosively propelled metal projectiles in self-destruct devices for rupturing fuel tanks of missiles and to release boosters and other mechanisms from space vehicles and other jet propelled devices. Self destruction is required when the missile or device is off-course and has assumed an erratic and uncontrolled path of travel.

The invention will be described and illustrated in connection with both of the above discussed applications, but it is by no means limited to these applications.

As respects the first application, the development of anti-satellite satellite weapons and other defensive devices for use against enemy missiles and satellites traveling in space is now a matter of prime military consideration. It is important to have available a means for destruction of enemy missiles, spy satellites and other type satellites traveling in space above the atmosphere. Conventional means for hurling projectiles, such as projection chambers, are out of the question for use in space applications because of weight and space considerations for the vehicle carrying them. Further, conventional projectile hurl-

2

ing devices could not be used on space vehicles because the recoil force of these devices would knock the space vehicle carrying them off course and out of its orbit. Accordingly, it is of extreme importance to have a projectile hurling device available for use on anti-satellite satellites to defend against enemy satellites, which is light and compact in construction and does not produce recoil forces upon projection of the projectile toward the enemy missile or vehicle.

10 As respects the second application, it is now standard practice to incorporate self-destruct devices in missiles and propelling devices for space craft to provide for automatic self-destruct of the missile or propelling device when the missile or space-craft is off course. Ordinarily, 15 self-destruct devices rupture fuel tanks and this results in destruction of the missile either through loss of pressure in the fuel tank, loss of fuel, explosions, or for other reasons. In the case of missiles filled with hypergolic propellants wherein fuel and oxidizer are carried in separate tanks, self-destruct is achieved by simultaneously rupturing both tanks to permit the fuel and oxidizer to come together and ignite so that the resultant violent reaction rips the missile apart, terminating the mission. Achieving self-destruct by causing structural damage to tanks or 20 parts of missiles is ordinarily accomplished with explosive bombs or shaped charges. Bombs or shaped charges are placed against the outside fuel tank walls, against tanks or 25 domes of fuel tanks, or upon the guidance mechanism.

Conventional methods of achieving self-destruct are 30 subject to a number of disadvantages. The damage to missile parts must be directional and specified and if two tanks containing hypergolic fluids are to be ruptured, rupturing of both tanks must be accomplished substantially simultaneously. When bombs are used, the fragmentation of the metal case is random and fragment particle sizes vary so that it is difficult to precisely control the direction of particles with accuracy to achieve destruction in the specified areas.

When linear shaped charges are used, damage is greatest 35 when standoff distances are exact and predetermined and this is not always possible of attainment. Shaped charges are more effective in penetrating masses of material and causing damage within a narrow specified radial diameter. When used against targets which require a wide area to be destructed, shaped charges are ineffective. Even when bombs or shaped charges can be placed 45 against the outside tank walls, against domes, or upon the guidance mechanisms, failures often result in propagation of the shock wave due to sharp bends or poor contact between joining strands.

A method and apparatus was disclosed in the copending application referred to above for explosively propelling flat plates of lead and lead alloys comparatively great distances for self-destruct space applications. As 55 further disclosed in that application, it has not been possible heretofore to explosively project plates of all metals and their alloys by the method described therein, but only plates of lead, and alloys thereof containing at least ten percent lead, could be propelled explosively more than a few centimeters without shattering.

It is therefore an object of this invention to provide an apparatus and method for propelling projectiles which can be used in outer space in connection with an anti-satellite satellite weapon.

It is another object of this invention to provide a method and apparatus for directionally and accurately propelling projectiles either in or outside the atmosphere without the use of a propelling chamber.

70 It is still another object of this invention to provide a method for accomplishing self-destruct of jet propelled missiles.

It is a further object of this invention to provide a method and apparatus for simultaneously rupturing a plurality of missile fuel tanks for the propose of self-destructing the missile.

It is another object of this invention to provide a method and apparatus for accomplishing self-destruct of missiles in outer space where the creation of shock waves is impossible because of the absence of air.

It is another object of this invention to provide a means for propelling thin plates of metal in general over great distances without shattering.

The invention includes a method for directionally propelling projectiles which consists, in one modification, in fitting one surface of a substantially flat metal plate which serves as the projectile over a corresponding surface of a sheet of explosive with a sheet of protective material such as plastic, serving as a buffer plate, between the metal plate and the explosive, and detonating the explosive to propel the metal plate flat-wise along a desired path with controlled accuracy. This modification provides for the destruction of one object only. The apparatus formed of explosive and metal plates is referred to herein as a destruct charge.

If the simultaneous destruction of two objects or two or more walls, such as, the walls of two propellant tanks of a missile is required, a metal plate with the buffer plate between it and the explosive charge is arranged on each side of the explosive charge to form a modified destruct charge and the assembly positioned between the two walls so that upon detonation of the explosive the walls will be substantially simultaneously ruptured by the plates.

In space applications, wherein the device is used in anti-satellite satellite applications the destruct charge or projectile assembly is mounted on a satellite and fired at another object traveling in space, with the use of fire control apparatus, the latter in combination with the projectile assembly constituting one modification of the invention. In the space application, it is generally expedient to use two plates in the projectile assembly even though the destruction of only one target is intended. This is because the use of a back-up plate provides a base for the plate which is being directed at the target to aid in keeping it on its flight path, and it also serves a recoil counteracting function. It is also desirable to use two destruct charges located on opposite sides of the vehicle to control or cancel out recoil forces.

The invention is best explained by reference to the accompanying drawings in which like parts are represented by like numerals, and in which,

FIG. 1 is a top plan view of the destruct device used in an anti-satellite satellite or as a self-destruct device;

FIG. 2 is a cross sectional view of the destruct device taken on line 2—2 of FIG. 1;

FIG. 3 is a cross sectional view of a modification of the destruct device of FIG. 2 in which single plates of lead and plastic are used;

FIG. 4 is a schematic showing of the destruct device arranged between propellant tanks, one containing oxidizer and the other containing fuel, the mixture of fuel and oxidizer forming a hypergolic mixture;

FIG. 5 is a schematic perspective view of a modification of the destruct device in which a rectangular shaped wafer is used, the case being omitted in this showing.

FIG. 6 is a schematic showing of a weapon satellite carrying the projectile assembly or destruct device of this invention and illustrating its application in space as an anti-satellite satellite, and

FIG. 7 is a schematic sectional showing of the weapon satellite of FIG. 6 showing schematically the various operating components of the satellite.

Referring to FIGS. 1 and 2, the weapon or destruct device represented generally by the numeral 10 comprises a solid explosive charge 12 having flat, parallel outer longitudinal faces 14 and 16 which are abutted by correspondingly flat buffer plates or wafers 18 and 20

of protective material. These plates are made with parallel longitudinal flat faces which correspond with the flat faces 14 and 16 of the explosive charge 12. Flat metal plates 22 and 24 are held securely against the protective

plates 18 and 20, respectively, by a metal case comprising a back plate 26 and a circular facing cover or cap 28, which is cup-shaped and provided with a circular horizontal flange 30 which is attached to back plate 26 by means of rivets 32 or other equivalent fastening means. It will be noted that the back plate 26 and cover 28 conform to the surfaces of the metal plates 20 and 22 and hold the entire assembly together in snug relationship. A detonator 34 is mounted at one end of the cover 28 in contact with the explosive charge 12. The purpose of the detonator is, of course, to initiate the shock wave which builds up to detonate the explosive 12 to propel metal plates 22 and 24 outwardly in opposite directions. The back plate 26 and facing cover 28 are made of readily flammable material such as aluminum or similar supporting material.

It is an important feature of the invention that the metal plates and buffer plates correspond and mate with the longitudinal flat faces of the explosives. It is this feature which provides directionality to the path of the metal plates and permits accurate propelling of these plates along a required trajectory. In the modifications shown, the faces of the explosive charge are parallel; however, the invention is not necessarily restricted to this requirement as obviously the flat plates could be propelled angularly to each other with the use of non-parallel faces on the explosive charge. It has been found that they can be propelled in a straight line perpendicular to the explosive face if the faces of the explosive are flat and the mating faces of protective plate and explosive correspond with each other.

Any conventional explosive may be used, such as, TNT, PBX, Composition A, PETN or other type high explosives. The material of the protective or buffer plates 18 and 20 may be chosen from a large number of non-metallic materials, preferably nylon, Teflon and fiber glass in a plastic matrix, or various plastics. The manner in which this material operates to prevent the metal plates 22 and 24 from shattering under the loading of the shock wave from the detonation of the explosive charge 12 is not known. These plates are referred to herein as "protective plates" or "buffer plates" to describe generally their function. Obviously, many non-metallic materials will function in this application and the invention is not restricted to the use of the recited materials as there are many equivalent plastics and other materials which will operate just as effectively. The detonator 34 may be made of conventional design and its construction is not critical.

The metal or alloy from which the metal plates 22 and 24 are constructed is not critical as all metals are suitable when used with the protective plates. Illustrative operative metals are silver, gold, cadmium, cobalt, chromium, copper, molybdenum, nickel, lead, tin, thorium, titanium, tantalum, vanadium, tungsten, zirconium, bismuth, iron, antimony, and alloys of these metals. Prior to this invention, as disclosed in the above-referred to application, the only metals known to be operative in the atmosphere without the protective plates were lead and alloys of lead containing at least ten percent lead as other metals shatter in the atmosphere under explosive loading after a few inches of travel. However, it has been found that with the use of the protective plates 18 and 20, all other metals can be used. Mercury can be used by incasing it in a suitable casing which conforms with the flat surfaces of the protective plates. The detonator 34 may be of conventional design and its construction is not critical.

Reference is now made to FIG. 3 in which there is shown a modification utilizing a single metal plate 22, a single protective plate 20 and explosive 12, the assembly of explosive, protective plate and metal plate being surrounded by a protective casing comprised of back

plate 26 and cover 28. The detonator 34 in this instance is positioned centrally of the explosive charge on the side opposite the prospective target as shown.

In FIG. 4 the application of the destruct device as a self-destruct device is illustrated. It is positioned between two propellant tank domes 38 and 40 of a missile or space vehicle and in this application the tanks are ruptured substantially simultaneously by the metal plates on either side of the explosive when the explosive is detonated.

In FIG. 5, there is shown a modification of the weapon device comprised of a flat metal rod and a flat rod of explosive having a protective rod of plastic or like material between them, the length dimension of the components being large in relation to the width dimension.

It is essential that the projectile plates of the destruct device be projected directionally and with accuracy. This is accomplished by making the mating surfaces of explosive, buffer plate and metal flat with no substantial voids in them. The amount of explosive used will of course be a factor in the velocity with which the plates are propelled. The size of the metal plates will also, obviously be a factor contributing to the velocity of the plates and the distance they will be propelled.

The destruct device of the invention was extensively tested using plates of various dimensions of a large number of metals, including those tested in the examples given below, without the protective plate of plastic positioned between explosive and metal. With the exception of lead and lead alloy plates all others shattered in no more than four or five centimeters of travel. The device was extensively tested with a number of metals using a protective plate of plastic between the metal and explosive and the following examples were selected from the tests. In these examples the double metal plate modification of FIG. 2 was used. In order to provide comparative results, an arrangement of a lead plate without the protective plate was used on one side of the explosive as a blank and a metal plate, hereinafter referred to in the examples as "the plate being tested," with a protective plate of nylon between it and the explosive was used on the opposite side of the explosive. Lead was used for the blank because it is the only metal from which a plate can be constructed which will not shatter if explosively propelled even a few centimeters without a protective plate positioned between it and the explosive before detonation. The metal plates used were 7 inches in diameter and $\frac{1}{16}$ inch thick. The protective plate was made of nylon 7 inches in diameter and $\frac{1}{8}$ inch thick. In all of the examples, the charge was supported by a wooden frame and was placed between two 55 gallon steel barrels a distance of 16 feet from each barrel with the flat sides of the unit facing the target barrels, with the exception that in Examples 3 and 4 the destruct device was 12 feet from the barrels.

Example 1

In the destruct device used in this example the metal plate being tested was constructed of lead. At the firing, the results of this test showed that the lead plate being tested produced a larger hole in its target barrel than did the lead plate being used as the blank. The size of the hole produced by the lead plate being tested was 6 inches by 8 inches.

Example 2

The destruct device used in this example had a steel plate as the plate being tested. Upon firing the device, the steel plate produced a hole in its target 12 inches by 8 inches, while the lead plate used as a blank produced a hole 4 inches by 6 inches.

Example 3

In this example the plate being tested was a brass plate. Upon firing, the brass plate completely destroyed the barrel with the sides of the barrel being peeled back

almost in a straight line. The lead plate split the side of the barrel the entire length and peeled the sides back approximately only half way around.

Example 4

5 In this example the destruct charge used had an aluminum plate as the plate being tested. Upon firing, the aluminum plate produced a hole in the target about 4 inches by 8 inches while the lead plate produced a hole 18 inches by 24 inches. It would appear that the lead plate was more effective in this example; however, there was no objectionable shattering of the aluminum plate and it produced a hole of substantial size for a relatively frangible metal of this type.

10 15 In this test another steel plate was used as the metal being tested. The steel plate formed a hole 12 inches by 18 inches in the target.

20 The examples graphically demonstrate that by the use of the protective buffer plate between the explosive and the metal plate, plates of metals other than lead can be explosively propelled at least 12-16 feet in the atmosphere without shattering and they are as effective for destruction of the target as lead plates used without buffer plates.

25 Example 1 shows that the use of a protective plate between a lead plate and the explosive adds to the effectiveness of the lead plate in the destruction of targets. In contrast to these results, many tests in which attempts were made to explosively propel plates made of metals other than lead without buffer plates showed that such plates of the size used in the examples could not be propelled more than a few inches without completely shattering and breaking apart.

30 35 It is seen from the above description that a method has been provided for directionally launching metal projectiles in the form of plates without the use of a projectile barrel. The method provides for the utilization in this manner of all types of metals. Plates made of any metal can be explosively propelled great distances without shattering. This invention makes possible the use of the destruct device in anti-missile-missiles and anti-satellite satellite devices.

40 45 Reference is now made to FIGS. 6 and 7 for a showing of the application of the destruct device in an anti-satellite satellite weapon system, the showing broadly depicting the combination of the destruct device with a fire control system transported on a satellite. The satellite carrying the destruct device is designated by the numeral 42. The systems carried by the satellite for launching the destruct charges comprise means for storing the destruct charges

50 55 such as destruct charge magazines or ammo cans, means for computing the range and velocity of the target such as a locator and range-velocity computer, means for stabilizing the satellite, means for directing the operations of the satellite, such as, a control telemetry transmitter, means for identifying the target such as a conventional IFF system and means for supplying power to operate the various systems. The systems outlined above for transporting and launching the destruct charge may be conventional systems commonly used to perform the functions indicated. They are illustrative of operative systems in use which can be used on the anti-satellite satellite weapon to provide an operative modification.

60 65 Referring to FIG. 6, six destruct charge projectile holders 44 are shown equally spaced around the satellite. The number used is not limited to six as any convenient number may be used. Each projectile holder is supported by the telescoping arm 46. In the preferred modification, the telescoping arms are stored inside the satellite as shown schematically in FIG. 7 and may be propelled into position with the destruct charge mounted thereon by means of a pyrotechnic propellant or other equivalent means which is automatically actuated upon the firing of one of the charges or which may be actuated by remote control. The telescoping arms are so mounted that when 70 75 one is propelled into position it automatically ejects the

arm it replaces and from which the charge has just been fired. The satellite can, of course, be operated without replenishment projectiles. The magazine for the destruct charges and telescoping arms at each station can be constructed to hold as many charges as necessary. If desired, the final charges may be so designed as to destruct the satellite itself so as to remove it from orbit or demolish it so that it will be unidentifiable by enemy inspection.

The target locator and range-velocity computer may be either ground controlled or self-directed upon operating instructions from earth. Approximate target vectors can be furnished the computer by earth telemetry and a conventional satellite target finding system located on the satellite takes over and uses this information for the final location of the target for its destruction. The target location system to be used may be a miniaturized Doppler radar system and/or a system similar to conventional radar directed anti-aircraft systems.

The destruct charges 10 are mounted in the projectile holders to rotate about the axis upon which they are mounted by conventional, directional drive mechanism. The telescoping arms 46 are also mounted to rotate around their long axes with the result that the destruct charges 10 can be rotated about two perpendicular axes in aiming them at a target. Conventional actuating means responsive to a control telemetry transmitter are provided for rotating the telescoping arms and destruct charges in response to information provided by the target locator and range-velocity computer.

Telescoping antennas 43 are shown spaced around the satellite for receiving signals for the various systems.

The firing system is constructed for coordination to provide for movement of the bidirectional charge to a predetermined firing position by Selsyn motors and to provide for stabilization of the charge prior to firing. This is facilitated by the fact that no media exists in outer space to change a target's course and speed.

A control telemetry and transmitter system is built in to direct the operations of the satellite. It functions to turn on the power supply, turn on the transmitters, supply the arming signal for the charges, plot in the target's approximate course and direction and, after firing, to deactivate the components of the apparatus.

In the preferred modification, a conventional IFF system is installed to prevent accidental destruction of friendly satellites and to insure destruction of enemy satellites. It is anticipated that attempts may be made to board the satellites by enemy inspection parties. An IFF system is necessary to ascertain whether the boarder or target satellite is friend or enemy. Failure of proper identification of the other satellite results in immediate automatic actuation of the major power supply and arming systems and destruction of the boarders by the bidirectional charges.

Power for the satellite is furnished by solar energy collected with mirrors represented schematically at 50 in accordance with conventional procedures. The power supply system is conventional and uses standard battery rechargeable cells utilizing solar energy to operate the silicon solar power generating sources. These power generating sources are built on the missile or they can be on a trailing tail-type of appendage. The power required to operate the satellite will be large when all systems are on a "go" basis but minimal when they are on a stand-by basis.

From the above description it is seen that the invention provides an effective anti-satellite satellite weapon for use in space against enemy satellites in which an effective destructive charge is provided which does not require the use of a projectile barrel and can be utilized on a satellite without excessive weight requirements. In this application of the weapon device in space, the flat plates will travel great distances in a straight line as there is no effect on them from gravity or an atmosphere. The advantage of this application is readily seen because it

does not require heavy launching equipment to be carried by the satellite where space and weight requirements are at a premium. Use of conventional weapons are prohibitive because of the large weight and space occupied by these weapons. Furthermore, these conventional weapons produce a recoil effect which would make it impossible to keep the satellite on its course.

The invention has been described by its application as a self-destruct device for simultaneously destructing opposing walls of missile fuel tanks and in an anti-missile-missile. Obviously, it is by no means limited to these applications as they are given for the purposes of illustration only. The invention may be used in a single projectile device shown in FIG. 3 for various purposes as well as in the dual projectile device of FIG. 2. The device finds use in any application wherein it is necessary or advantageous to propel a projectile without the use of a projectile chamber. The invention has many applications for use in connection with space vehicle and missiles traveling in the atmosphere, or in outer space wherein conventional explosives cannot be used to effect damage by traveling shock waves.

While the term "plate" has been used herein to describe the metal projectile, this is not to be considered as restricting the shape of the projectile as practically any shape of projectile can be used, the main requirement being that the adjacent surfaces of explosive and protective plate and of protective plate and explosive conform and be substantially flat.

It is therefore to be understood that various modifications and changes may be made in the construction and arrangement of parts of the present invention without departing from the spirit and scope thereof as defined by the appended claims. Various changes and modifications may be made in carrying out the present invention without departing from the spirit and scope thereof. Insofar as these changes and modifications are within the purview of the annexed claims, they are to be considered a part of this invention.

40. What is claimed is:

1. The method of substantially simultaneously rupturing a plurality of spaced apart walls by hurling projectiles against them without the use of a projectile chamber which comprises: positioning a piece of explosive material having at least two flat opposed faces between said spaced apart walls with each flat face of explosive facing a wall; supporting a flat buffer plate having opposed first and second flat surfaces contiguous to each of said opposed faces of explosive with contiguous faces of explosive and first surfaces of buffer plates conforming to each other; supporting a metal plate having at least one flat face contiguous to each of said second flat surfaces of the buffer plates with the flat faces of the metal plates conforming with the contiguous second surfaces of the buffer plates; and detonating said explosive charge to simultaneously and directionally propel said plates flatwise against said walls to rupture them with a greater destructive effect than would be achieved without the use of said buffer plates.

2. The method of claim 1 in which said spaced apart walls are walls of fluid tanks containing fluids to be mixed and the shattering of said walls results in mixing of said fluids.

3. The method of rupturing a wall of a body by hurling a projectile against it without the use of a projectile chamber which comprises supporting a flat metal plate having frontal surface dimensions greater than its thickness in front of said wall with one face of the metal plate facing a wall and in line therewith and the other face of said plate contiguous to and conforming to a flat face of a flat buffer plate which is supported with its other flat face contiguous to a corresponding flat face of an explosive charge; and detonating said explosive charge to propel said metal plate directionally against said wall to rupture

it with a greater destructive effect than would be achieved without the use of the buffer plate.

4. The method of destroying objects traveling in space by hurling projectiles against them without the use of a projectile chamber which comprises mounting on a space vehicle a destruct charge comprising an explosive charge having opposing flat faces with a flat buffer plate having opposed flat surfaces and a flat metal plate having at least one flat face supported adjacent each flat face of the explosive charge in the order recited and the contiguous flat faces of metal plates and buffer plates and buffer plates and explosive charge conforming to each other; positioning said destruct charge so that the exposed face of one of the metal plates is aimed along a collision course with said object; and detonating said explosive charge; whereby said metal plates are propelled in opposite directions with said one of the metal plates propelled along said collision course into said object to strike it with a greater destructive force than would be achieved without the use of said buffer plates.

5. A device for propelling a projectile towards a target without the use of a projectile chamber comprising: a barrelless support member; a high explosive charge having at least one flat face and mounted on said barrelless support member; a buffer plate having a first flat face contiguous and precisely conforming to a flat face of said explosive charge, and a second flat face; a metallic plate having at least one flat face; said buffer plate located between said explosive charge and said metallic plate with its second flat face contiguous to and precisely conforming to a flat face of said metallic plate; and detonating means connected to said high explosive for detonating said charge; whereby upon detonation of said detonating means said metallic plate is directionally propelled towards said target without the use of a projectile chamber to provide a greater destructive effect upon striking said target than would be achieved without the use of said buffer plate.

6. The destruct charge of claim 5 in which the buffer plate is made of non-metallic material.

7. The destruct charge of claim 5 in which the buffer plate is made of plastic material.

8. The destruct charge of claim 7 in which the buffer plate is made of a material from the class consisting of nylon and polytrifluorochloroethylene.

9. The destruct charge of claim 8 in which said buffer plates are made of non-metallic material.

10. The destruct charge of claim 8 in which said buffer plates are made of a plastic.

11. The destruct charge of claim 8 in which the buffer plates are made of a material from the class consisting of nylon and polytrifluorochloroethylene.

12. A device for propelling a projectile towards a target without the use of a projectile chamber comprising: a barrelless support member; a high explosive charge having opposed flat faces mounted on said barrelless sup-

port member; a buffer plate having opposed flat surfaces supported on each side of said explosive charge with a flat face of the explosive charge and one flat face of the buffer plate contiguous and conforming to each other; a metal plate having at least one flat face supported contiguous to each of said buffer plates with a flat face of a metal plate and the other flat surface of a buffer plate contiguous and conforming to each other; and detonating means connected to said high explosive for detonating said charge; whereby upon detonating said detonation means said metallic plate is directionally propelled towards said target without the use of a projectile chamber to provide a greater destructive effect upon striking said target than would be achieved without the use of said buffer plate.

13. A weapon system for destroying an object traveling in space without the use of a projectile chamber comprising: in combination, a space vehicle; a destruct charge supported on said space vehicle comprising an explosive charge having opposed flat surfaces; a flat metal plate having opposed flat faces supported adjacent each of the flat surfaces of said explosive charge; a flat buffer plate having opposed flat faces supported between said explosive charge and each of said metal plates with its flat faces contiguous to and conforming to the respective flat faces of explosive and metal plates; means for positioning said destruct charge so that the exposed face of one of the metal plates is aimed flat-wise on a collision course with said object; and means for detonating said explosive to propel said metal plates in opposite directions and said one metal plate directionally along said collision course to provide a greater destructive effect upon striking said object than would be achieved without the use of said buffer plate.

14. The weapon system of claim 13 in which the buffer plates are made of non-metallic material.

15. The weapon system of claim 13 in which the buffer plates are made of plastic.

16. The weapon system of claim 13 in which the buffer plates are made of a material from the class consisting of nylon and polytrifluorochloroethylene.
